UNITED STATES PATENT OFFICE

114,532

DESIGN FOR LITHOGRAPHED SHEET METAL FOR METAL CONTAINERS

Everett E. Engstrom, White Plains, N. Y., assignor
to McKeesport Tin Plate Corporation, New
York, N. Y., a corporation of Delaware

Application March 4, 1939, Serial No. 83,344

Term of patent 7 years

To all whom it may concern:

Be it known that I, Everett E. Engstrom, a citizen of the United States and a resident of White Plains, county of Westchester, and State of New York, have invented a new, original, and ornamental Design for Lithographed Sheet Metal for Metal Containers, of which the following is a specification, reference being had to the accompanying drawing, forming a part thereof, where-

in the figure is a plan view of lithographed sheet metal for metal containers showing my new design.

I claim:

The ornamental design for lithographed sheet metal for metal containers, substantially as shown.

EVERETT E. ENGSTROM.
